UNITED STATES PATENT OFFICE.

WILLIAM ARTHUR, OF NEW HAVEN, CONNECTICUT.

COASTING-REGISTER.

1,319,454.

Specification of Letters Patent.

Patented Oct. 21, 1919.

Application filed April 3, 1918, Serial No. 226,532. Renewed March 13, 1919. Serial No. 282,493.

To all whom it may concern:

Be it known that I, WILLIAM ARTHUR, a subject of the King of England, residing at New Haven, Connecticut, in the county of 5 New Haven and State of Connecticut, have invented certain new and useful Improvements in Coasting-Registers, of which the following is a specification.

This invention relates to certain new and 10 useful improvements in coasting registers, and pertains more particularly to a register employed in connection with electric cars.

The primary object of the invention is to 15 enable a computation fair to the motorman to be made of coasting time as compared with the actual running time of the car. Thus, it frequently occurs that a tie-up occurs for reasons beyond the control of the motorman, and in such cases the motorman's 20 record of coasting time compared to the total time he has been on the car will not be a fair indication of his efficiency. An example will illustrate this. Suppose a motorman has been on his car 10 hours one of 25 which he has coasted 2 hours and in addition has suffered a delay of 2 hours. If his coasting time is compared with the total time his coasting percentage becomes $\frac{2}{10} \times 100 = 20\%$; but when compared with the actual 30 length of time the car has been operated becomes $\frac{2}{12} \times 100 = 25\%$. It is therefore highly important to be able to compare the coasting time with the actual running time. Accordingly, the present invention, briefly, 35 proposes to employ a clock mechanism which is partially wound upon each brake application so as to render the clock active throughout the time of the longest run of a car between stops. For example, if the time 40 in running between the longest stops of the car is five minutes, then the clock is wound so as to remain active throughout such period, and to cease running or become inactive upon the expiration of such period, 45 so that if the car is delayed for any reason, the clock will stop, and will only be again restarted for a like period upon the next application of the brakes. By this means the clock mechanism is running only so long as 50 the car is running plus the predetermined amount; and if the car stops running the

clock mechanism automatically stops running after the predetermined length of time has elapsed. In this way actual coasting time can be fairly computed as compared 55 with actual running time of the car.

In the drawings:

Figure 1, is a front elevation of the invention showing the latter in a case with the front of the latter removed;

Fig. 2, is a section taken on line 2—2 of Fig. 1; and

Figs. 3 and 4, are views in side elevation and partly in section, illustrating certain of the parts in different positions, other of 65 the parts being omitted.

In proceeding in accordance with the present invention, a case 1, is employed to which is secured a cylinder 2 connected to a pipe 3 leading from the air brake line of the 70 car. A plunger or piston 4 reciprocates within the cylinder and has a stem 5 carrying spaced collars 6 and 7, the stem being suitably tensioned, for example, by means of a coil spring 8 bearing on the collar 7 and 75 housed in a sleeve 9.

An electro-magnet 10 is mounted within the case 1, and attracts upon energization, an armature 11 mounted on a hinged arm 12, the latter having a right angular part 13, 80 formed with a foot 14, while its upper end is free as indicated at 15 to provide a stop finger. A suitable clock-works or mechanism 15^a is mounted in the case and operates a shaft 16 which has slight sliding 85 movement, and which is tensioned by a coil spring 17, the shaft carrying time registering wheels 18 and a clutch member 19 on its end. This clutch member 19 is for engagement with a complementary clutch member 90 20 which latter is operatively connected to the coasting-registering wheels 21 and with the latter is mounted on a shaft 22 suitably journaled in bearings 23.

A shaft 24 located below and at right 95 angles to the shaft 16 carries a radial arm 25 for engagement with the collar 6 and a second radial arm 26 for wiping engagement with the end 27 of the shaft 16.

The means for winding the clock 15^a embodies a dog or trip 28 pivoted on the winding shaft 29 of the clock and having its end 100

30, arranged to lie in the path of movement of the collar 6, said end 30 in turn being in the path of movement of an arm 31 rigidly secured to the winding shaft 29 of the clock. 5 Arm 31 is tensioned by a coil spring 32 and is limited in its down movement by a stop pin 33. Collar 7 carries a starting and stopping means in the form of a light spring 34 which bears on a brake wheel 35 mounted on 10 the balance wheel shaft 36 of the clock.

In operation, when the brake is applied, the plunger 4 is moved upwardly causing the lower collar 6 to strike against the end 30 of the dog or trip 28, and the latter in 15 turn strikes against the arm 31 moving the latter to partially wind the clock. This upward movement of the stem 5 of the plunger causes corresponding movement of the starting and stopping element 34, effecting starting 20 of the clock. The stem in moving upwardly causes its collar 7 to wipe against the part 13 of the arm 12 and pass the latter whereupon the arm 12 will gravitate after 25 passing of the collar 7, and will engage beneath the collar holding the stem in the position of Fig. 3. The clock thus continues 30 running or remains active, and through the shaft 16 actuates the time registering wheels 18. If now the motorman releases the 35 brakes, the parts will still remain in the position of Fig. 3, and if he then throws the current on, the magnet being in a circuit W with the motor controller C in the circuit S of the latter, will be energized attracting the armature 11, and moving the end 15 of the 40 part 13 of said arm out of its supporting engagement with the collar 6 whereupon the stem 5, under the impulse of the spring 8, will move the stem downwardly, but the 45 stem will be prevented from making a complete down movement because the movement of the arm 12, has brought the foot 14 thereof to a position so as to engage and arrest the full or complete down movement 50 of the plunger, as depicted in Fig. 4, of the drawings. The clock will consequently remain active and will continue movement of the time registering wheels 18.

When the motorman throws his power off 55 the magnet 10 will be deenergized, releasing the arm 12, and permitting the spring 8 to effect a complete down movement of the plunger stem, the parts being then in the position of Fig. 1. The car is now coasting 60 and the coasting registering wheels 21, will be actuated, since upon complete down movement of the plunger, collar 6 thereof strikes the arm 25, and the latter rocks the shaft 24. The rocking of the shaft in turn causes corresponding movement of the arm 26 of said shaft thereby effecting wiping of 65 arm 26 against the end 27 of the shaft 16, sliding the latter so as to cause its clutch member 19 to engage the clutch member 20

of the coasting registering wheels 21, and thereby actuating the latter to register the coasting time of the motorman.

From the foregoing it will be apparent that in order to obtain a coasting record, the motorman must have his brakes and power 70 off, since the operation of the clutch to clutching position to actuate the coasting registering wheels 21, can only be effected when the parts are in the position of Fig. 1, in which the plunger is at the limit of its 75 down movement. Also, since the clock is wound upon each application of the brake to insure its active state throughout the predetermined period between the longest run of a car between stops, it will be apparent that 80 any delay in the car movements beyond such time, will bring the clock to a stop so that the per cent. of coasting based on actual running time of the car can be computed with 85 fairness to the car motorman or operator. As long as the clock is active the shaft 16 connected to the clock will continue operation to indicate the running time of the car.

The device thus indicates the relation between the actual running time of the car and 90 the coasting time by providing a constantly actuated time register which latter is rendered inactive upon any stoppage of unusual length of time for example, tie-ups, accidents and the like and a coasting register 95 which operates only during actual coasting.

It will be understood that the term register comprehends a recorder or recorder printing mechanism as well.

If desired a valve 34' may be employed in 100 the pipe 3, to shut off the air from the cylinder 2, in which event the clock must be maintained wound by manually winding with a key, so as to register power on only 105 as compared with running time, but without the advantage of obtaining a reading of actual running time.

What is claimed is:—

1. In a coasting register, a time register, means to operate the time register, a coasting register, means controlled by the brake controller for storing a predetermined quantity of power in the first named means upon each application of the brakes to thereby render the time register active throughout a 115 corresponding period and means controlled by the brake controller and by the motor controller for controlling the operation of the coasting register.

2. In a coasting register, a normally active time register, means for automatically effecting operation of said register at intervals throughout a predetermined period, a coasting register, and means controlled by the motor controller and by the brake controller for controlling the operation of the coasting register.

3. In a coasting register, a time register,

- means to operate the time register, a coasting register, selective means to operate the coasting register from the time register, means controlled by the brake controller for 5 storing a predetermined quantity of power in the first named means upon each application of the brakes to thereby render the time register active throughout a corresponding period, and means controlled by the brake controller and by the motor controller for 10 controlling the operation of the selective means.
4. In a coasting register mechanism, a time register, a clock mechanism for operating said time register, means controlled by the brake controller for effecting partial winding of the clock mechanism upon each operation of said controller, a coasting register, means for operating the coasting register by said clock mechanism, and means controlled by the brake controller and by the motor controller for controlling the operation of the coasting register. 15
5. In a coasting register mechanism, a time register, a clock mechanism for actuating the time register, a coasting register, a clutch between the time and coasting registers to operate the latter from the former, a plunger controlled by the brake controller, means controlled by the plunger for effecting partial winding of the clock mechanism upon each application of the brakes and for starting the clock, means for holding the plunger against return movement following 20 actuation thereof, means controlled by the motor controller for holding the plunger against a complete return movement following application of the power, and means controlled by the plunger for operating said clutch when the power is off and the brakes are off. 25
6. In a coasting register mechanism, a time register, a clock mechanism for actuating the time register, a coasting register, means for operating the coasting register from the time register, a brake controller and a power controller, means operated by one of said controllers for automatically effecting partial winding of the clock, and means controlled by the brake and motor controllers for controlling the operation of the coasting register. 30
7. In a coasting register mechanism, a time register, a coasting register, a brake controller and a motor controller, means for automatically effecting operation of the time register throughout a predetermined period controlled by the application of one of said controllers, and means controlled by said controllers for controlling the operation of the coasting register. 35
8. In a coasting register mechanism, a time register, means for effecting operation of said register at intervals throughout peri- 40
- ods of predetermined length, a coasting register, and means controlled by the motor and brake controllers for controlling the coasting register. 45
9. In a coasting register mechanism, a time register, means for effecting operation of said register at intervals throughout periods of predetermined length, a coasting register, means for operating the coasting register from the time register, and means controlled by the motor and brake controllers for controlling the coasting register. 50
10. In a coasting register mechanism, a time register, a clock for operating same, means for effecting partial winding of the clock at intervals to effect corresponding operation of the time register throughout periods of predetermined lengths, a coasting register, means for operating the coasting register from the time register, and means controlled by the motor and brake controllers for controlling the coasting register. 55
11. In combination with the brake and motor controllers of a trolley car or the like, means to indicate the time consumed in making the run of the car, means to indicate the time during which the car coasts, means controlled by one of said controllers for effecting operation at intervals of said time indicating means for periods of predetermined lengths, and means controlled by the brake and motor controllers for controlling the coasting indicator. 60
12. In a coasting register mechanism, a time register, a coasting register, means between the two registers for effecting selective operation thereof simultaneously, an electro-magnet controlled by the motor controller, means controlled by the brake controller for effecting periodic operation of the time register throughout intervals of predetermined lengths, and means controlled by the electro-magnet and by the brake controller for controlling the operation of the selective means. 65
13. In a coasting register mechanism, a time register, a coasting register, means between the two registers for effecting selective operation thereof simultaneously, an electro-magnet controlled by the motor controller, a plunger controlled by the brake controller, means controlled by the plunger for effecting periodic operation of the time register throughout intervals of predetermined lengths, means controlled by the plunger for controlling the operation of said selective means, and means controlled by the electro-magnet for controlling the plunger so as to allow the latter to operate the selective means only when the power is off and the brakes are off. 70
14. In a coasting register mechanism, a time register, a coasting register, means be- 75

tween the two registers for effecting selective operation thereof simultaneously, means controlled by the brake controller for effecting periodic operation of the time register throughout intervals of predetermined lengths, energizable means controlled by the motor controller, means operated by the plunger to effect operation of said selec-

tive means, and means controlled by the energizable means for controlling said means controlled by the brake controller to allow the latter to operate the selective means only when the power is off and the brakes are off.

In testimony whereof I affix my signature. 15

WILLIAM ARTHUR.
